UNITED STATES PATENT OFFICE

SAMUEL L. MARCUS, OF CHICAGO, ILLINOIS

SHOE CONSTRUCTION

Application filed July 19, 1928. Serial No. 293,946.

This invention relates to improvements in shoe construction and the object thereof is to provide a novel shoe, sole and arch construction and to so construct the shoe that it will not give, yield, or break down under weight of the wearer at the arch and will obviate the objections heretofore present in shoes having metal or spring arches as well as provide comfort for the wearer by providing an arch of leather which bridges the customary space at the arch beneath the sole, and between the ball of the foot at the metatarsal bones at the sole of the shoe and the heel to give comfort to the wearer without detracting from the appearance of the shoe.

A further object of the invention is to provide a specially constructed shoe which is principally intended for persons, particularly men of abnormal weight, or for those having weak arches, which is accomplished by forming the arch, which is preferably an extension of the sole proper, with a central depression producing a concavity on the inner side of the arch portion so that the central portion of the outer layer of the arch is flush with the sole. The concavity of the arch just referred to is then filled in between points adjacent the metatarsal bones and the heel, with a sufficient number of layers of leather to produce a solid, stiffened and reenforced arch portion which is raised or humped to fit the arch of the foot and give support to the same and the weight of the body thereon. These layers, which are used to fill in the concavity in the arch, are preferably glued together or otherwise secured in position and are also glued or otherwise secured to the inner side of the arch portion of the sole.

Other objects and advantages will be apparent as the description proceeds.

In the accompanying drawings:

Figure 1 is a side elevation of a shoe constructed in accordance with the invention.

Figure 2 is a longitudinal sectional view taken on the section line 2—2 of Figure 4.

Figure 3 is a transverse sectional view taken on the section line 3—3 of Figure 4.

Figure 4 is a bottom plan view with the heel in dotted lines.

Figure 5 is a bottom plan view before the application of the outer sole and the heel.

Figure 6 is a bottom plan view of the inner sole and layers forming the fill-in producing the arch.

Figure 7 is a top plan view of the outer sole.

Figure 8 is a perspective view of the heel detached.

Figures 9, 10, 11, 12 and 13 are sectional views taken on the section lines 9—9, 10—10, 11—11, 12—12 and 13—13 of Figure 7, and

Figures 14, 15 and 16 are sectional views taken on the section lines 14—14, 15—15 and 16—16 of Figure 8.

Referring to the drawings in detail, in which like reference characters designate corresponding parts throughout the several views, the shoe upper is designated at 1 and may be of the usual type with the lower part or vamp 2, toe 3 and counter heel portion 4. The inner sole is designated at 13' and the inner sole lining at 6 as distinguished from the outer sole 5 and the usual welt 7. The arch portion is designated at 8 and is a continuation of the outer sole while the heel is designated at 9.

The arch portion of the outer sole is formed by means of dies to produce a concavity 10 in the inner side of the arch portion of the sole, said concavity narrowing toward the heel portion and sloping up on opposite sides as indicated at 11 while the heel portion of the sole 5 slopes downwardly to said concavity in concave formation as indicated at 12.

It will be noted that the concavity 10 extends flush with the ball portion of the sole 5 and the bottom of the heel 9 and the concavity is filled in which a sufficient number of layers 13 of leather or other suitable material glued or otherwise fastened together,

so that the inner side of the arch portion of the sole at the concavity 10 will be flush with the inner side of the tread portion of the sole 5. These layers include a top layer 13' forming the insole of the shoe as disclosed more particularly in Figures 5 and 6 as well as in Figure 2, have sloping sides and are gradually smaller toward the bottom and taper off at their edges and toward the inner sole 13' so as to conform to the top face of

the sole 5 and the concavity therein produced by the portions 10, 11 and 12. This filler extends between the ball of the foot at the metatarsal bones and the heel of the foot from slightly in back of the front edge of the heel 9 of the shoe at the bottom layer thereof and is inclined rearwardly to a point almost to the rear of the heel at the top layer.

When the inner sole and filler are secured in position, the outer sole is placed thereover and secured in position to the upper, by pegs or otherwise, in conjunction with stitching indicated at 14, including the inturned bottom portions of the shoe upper designated at 2 and 4, and shown more particularly at 15 in Figure 5 of the drawings. This it will be observed, produces an arch which is humped or arched and of downwardly tapering formation as well as tapering toward its opposite sides and the ends, and in which the concavity or arch portion 10 is flush with the bottom of the sole 5 and the bottom of the heel 9, thereby reinforcing the shoe at the arch portion of the foot and preventing the same from giving, yielding or breaking down under the weight of the wearer. With this construction, it is unnecessary to further strengthen the arch by means of the usual spring-steel arch supports or strips of steel secured underneath the heel and extending lengthwise of the arch between the inner and outer layers of the sole to a point about in line with the ball of the foot or otherwise. The insole 13 and sections 13 of the arch are formed by layers of leather which are glued or otherwise secured together and this reinforcing portion disclosed more particularly in Figure 6 is made up and properly shaped with sloping sides as indicated at 16 in Figures 5 and 6 of the drawing. The purpose of this is to cause the reinforcing layers of the arch to conform to the concavity 10 and the side portions 11 and heel 12 of the outer sole at the top of the latter, as disclosed in Figure 7 so that when the outer sole and heel are applied, the arch will be bridged between the tread or ball portion of the shoe sole adjacent the metatarsal bone and the bottom of and slightly under the heel at the bottom but inclined rearwardly to a point near the rear of the heel at the top, as disclosed more particularly in Figures 1, 2 and 3 of the drawing. However, owing to the tapering formation of the reinforcing arch 10, together with the layers, 13, the latter will slope upwardly towards opposite sides of the front edge 17 of the heel 9 and render the reinforcing arch undiscernible while at the same time giving the necessary strength to sustain the weight of an abnormally heavy person. The result will be extreme comfort for those having weak arches or for heavy persons, since the arch will not give, yield or break down under the weight of the wearer.

In connection with the heel 9, attention is

directed to the fact that this heel is made up of a series of layers or lifts and these layers are cut out or concaved on the inside, or top, as indicated at 18 in Figure 8 of the drawing so as to conform to the bottom of the outer sole with the filling comprising the arch. Preferably, the outer sole is cut off or recessed slightly as indicated at 19 in order to receive the heel portion 9 thereon at its bottom layer 20. This is due to the fact that the recessing or cutting out of the heel 9 as indicated at 18, is so formed that all of the layers are cut through except a portion of the bottom layer of the heel as indicated at 20. Of course, the heel while preferably made of leather, may be of any other suitable material desired, such as rubber.

While I have described what I consider to be the preferred form, it is to be understood that various changes in the proportion, construction and arrangements of the parts may be made from that shown and described, without departing from the spirit and scope of the invention.

Having thus described my invention, what I claim is:

1. In a shoe construction, an outer sole having a depressed arch portion, a series of connected layers filled into said arch portion, and a heel fitting the sole and conforming with the heel portion thereof, said depressed arch portion being flush with the bottom of the sole and heel.

2. In a shoe construction, an upper, an inner sole attached to the upper, an outer sole attached to the inner sole and upper and having a depression at the arch, a heel attached to the outer sole at the heel portion of the shoe and concaved at the top to fit the same, and a filling in said depression between the inner sole and the outer sole, the depressed arch portion lying flush with the bottom of the outer sole at the ball or tread of the shoe and the bottom of the heel.

3. A shoe construction having an inner sole with a thickened arch portion produced by a series of layers secured together and graduating in size to the bottom, said layers being successively smaller toward the bottom to provide oppositely sloping sides and front and heel portions, an outer sole having a concavity at the arch portion formed by depressing the sole to provide oppositely inclined side portions and a heel having a concavity at the top narrowing centrally at the front of the heel to fit the bottom formation of the outer sole at the heel, the outer sole under the concavity of the arch portion lying flush with the bottom face of the tread of the outer sole and the bottom face of the heel.

4. In a shoe construction, an upper, an inner sole secured to the upper, said inner sole composed of layers glued together in tapering formation to provide oppositely sloping

side portions at the arch and an upwardly sloping portion toward the heel, an outer sole secured to the inner sole and upper and having a depression at the arch providing oppositely upwardly sloping sides, the concavity narrowing toward the heel and the heel portion being concaved to fit the arch portion of the inner sole whereby the arch portion of the shoe and the outer sole will lie flush with the bottom of the tread portion of the sole at the ball of the shoe, and a heel having a top concavity fitting the heel portion of the outer sole and secured thereto so that its bottom face will be flush with the arch portion of the sole and the tread of the sole at the ball portion thereby reinforcing the arch against give, yield or breaking down under the weight of the wearer.

5. In a shoe construction, an outer sole having a depressed arch portion, a series of layers secured together and filled into said arch portion and tapering upwardly at the sides and toward the opposite ends between the metatarsal bones at the front and under the heel at the rear, and a heel fitting the sole and conforming with the heel portion thereof, the depressed arch portion lying substantially flush with the ball portion of the outer sole and the bottom of the heel.

30 6. A shoe construction including an inner sole, a filler secured thereto and producing a thickened arch portion of raised formation and tapering towards opposite ends, an outer sole having a concavity at the arch portion receiving the filler and a heel having a cavity fitting the sole, the bottom of the sole under the concavity at the arch portion of the outer sole lying flush with the bottom of the heel and the tread of the outer sole.

40 7. A shoe construction having an inner sole with a thickened arch portion, an outer sole having a concavity at the arch portion formed by depressing the sole and a heel concavity fitting the inner sole, and a heel having a concavity at the top extending to the front of the heel to fit the bottom face of the arch, the bottom of the sole at said concavity at the arch portion lying flush with the bottom of the tread of the outer sole and the bottom face of the heel.

50 8. In a shoe construction, an outer sole having a depressed arch portion, an inner sole, a filler attached to the inner sole and fitting the depression of the arch portion between the metatarsal bones at the front and under the heel at the rear, and a heel fitting the sole and conforming to the heel portion thereof, said depressed arch portion lying flush with the tread of the sole and the heel.

60 9. A shoe construction including an inner sole, an outer sole having a concavity, an arch portion, a filler between the inner sole and outer sole producing a thickened arch portion of raised formation tapering toward opposite ends within the concavity and a heel to

which the outer sole is secured, the bottom face of the concavity at the arch portion of the outer sole lying flush with the bottom of the heel and the tread of the outer sole.

10. A shoe construction, having an outer sole having a depressed arch portion, an inner sole, a filler between the inner and outer soles and fitting the depression of the arch portion, and a heel secured to the outer sole, the depressed arch portion of the outer sole having its bottom face lying flush with the tread of the sole and the bottom of the heel.

11. A shoe construction, having an outer sole with a depressed arch portion forming a top concavity the bottom face of which is flush with the bottom face of the heel and the bottom of the sole at the ball of the tread and the sides of which are inclined upwardly to the side edges of the arch.

12. A shoe having an outer sole and a heel, said sole extending the full length of the shoe and inclined to the top of the heel at the back, and an arch portion depressed to form a top concavity and the bottom face of the longitudinal central part of which is flush with the bottom of the heel and the tread of the sole and the sides of which slope upwardly and outwardly toward the sides of the arch of the sole.

In testimony whereof I affix my signature.

SAMUEL L. MARCUS.
